UNITED STATES PATENT OFFICE.

RICHARD D. GALLAGHER, OF CHICAGO, ILLINOIS, ASSIGNOR TO ROOS FOUNDRIES, INC., OF CHICAGO, ILLINOIS, A CORPORATION OF ILLINOIS.

RERAILER OR CAR REPLACER.

Application filed March 2, 1922. Serial No. 549,404.

To all whom it may concern:

Be it known that I, RICHARD D. GALLAGHER, a citizen of the United States, residing at Chicago, in the county of Cook and State of Illinois, have invented certain new and useful Improvements in Rerailers or Car Replacers, of which the following is a specification.

My invention relates to rerailers or car replacers which are readily portable, and which may be quickly and easily put in place or removed without having to spike any of the several elements comprising my invention to the ties.

10 The invention is especially adaptable to industrial railways where there are oftentimes very shallow ties employed or in some instances where no ties are employed at all.

An object of the invention is to provide a 20 car replacer which may be secured in position without spiking.

Another object is to provide a car replacer which may be secured in position by attachment to a rail and clear of the ties.

25 Another object of the invention is to provide a car replacer suitable for either outside or inside replacement and which may be readily applied to track rails without spiking, bolting, or the like.

30 A still further object of the invention is to provide a replacer which may be used in connection with light industrial railways and securely applied in position without attachment to ties.

35 A still further object of the invention is to provide a car replacer including a clamp whereby said replacers may be quickly fixed in position by actuation of a single clamping member.

40 A further object of the invention is to provide a car replacer which may be easily and quickly clamped in position by means of an eccentric clamp.

Another, and still further object of the 45 invention, is to improve car replacers for successful commercial use.

The above recited and other objects of my invention will be apparent from the following description and drawings, and will be 50 particularly pointed out in appended claims.

In the drawings:

Figure 1 is an elevational view of my invention as applied to an outside replacer.

Figure 2 is a view similar to Figure 1

showing the invention applied to an inside replacer but with the clamp in engagement with the rail instead of the replacer casting.

Figure 3 is a top plan view of the clamp of my invention.

In the drawings 5 is a T-rail of standard 60 section and 6 is an outside replacer. The contour shape and arrangement of this casting is in accordance with present practice except that there is no need for providing spike holes in the casting when used with 65 my invention. It will be noted that the casting 6 has protruded lugs 7 for resting against the web of the rail 5 and which also rest on the top of the flange of the rail. Intermediate the length of the casting there 70 are downwardly extending lugs 8 and 9 for receiving the clamp of my invention.

In Figure 2, I have shown an inside replacer 10 which is provided with proper flanges and rests for guiding the wheel onto 75 the track 11. It is understood that as arranged in the drawings the wheels of the car which have become displaced are in Figure 1 on the outside, that is, at the left of the rail, and in Figure 2 on the inside, that is 80 at the left of the rail in this figure so that the replacer castings 6 and 10 respectively must be so fashioned as in the first instance to direct the flange of the wheel over the head of the rail, while in the second instance to direct the flange of the wheel against the inner side of the rail, that is at 85 the left hand side thereof.

The replacer casting 10 is provided with lugs 12, 13 and 14 similar to lugs 7, 8 and 9 shown on casting 6.

The clamp of my invention which I employ to secure the replacer castings 6 and 10 to the track rails rather than to the ties, comprises a metal strap 15 having one end 95 upturned as at 16 to form a hook for hooking over a flange either of the rail 5 in Figure 1 or of flange 17 formed on the rear sides of replacer castings. In Figure 1 the hook is shown as applied to the rail 5 with 100 the body of the strap 15 extending underneath the rail and the replacer casting 6. Depending lugs 8 and 9 on the casting 6 overlie the edges of the strap 15 to prevent displacement of the same with respect to the 105 replacer casting. The other end of the strap is formed with a yoke in which is mounted a bolt 18 in vertical position. The bolt 18

serves as an axis for eccentric cam 19, the outline of which is shown in full lines in Figure 3. The yoke 18 extends sufficiently to permit the cam 19 to be swung through 360 degrees if desirable. In the operative face of the cam there are provided a series of openings 20 in which may be inserted a suitable tool for turning the cam to securely lock the replacer casting against the track rail. There are three such openings shown 10 as I have found it necessary to move the tool from one position to another in securing proper clamping engagement.

The operation of the device is as follows: 15 When it is desired to apply an outside replacer such as shown in Figure 6, the replacer casting is put against the outside of the rail 5 and strap 15 is then passed under the casting and the rail and hooked over the 20 inside flange of the rail; thereupon a suitable tool is inserted in one of the openings 20 of the cam 19 and the same turned until it is in tight engagement against the flange 17 of the casting. It will be noted, therefore, 25 that the replacer casting is held firmly in position against the rail by the clamp and that no spikes, bolts or other means are necessary to maintain replacer casting in position.

In applying the clamp to the inside replacer such as shown in Figure 2 the replacer is put against the inside of the track rail 11 and the clamp is applied so that the strap extends underneath the track rail 11 and the replacer casting with the hooked end 30 16 over the ledge 17 on the replacer casting 10; then by application of a tool to the cam 19 this is moved against the rail web to secure a tight wedging fit of the replacer casting with respect to the rail.

40 By reason of the construction of the clamp of my invention it is possible to apply a clamp in such a manner as to always permit access to the clamp so as to securely fasten the replacer casting in position. In Figure 45 1 the clamp is against the replacer casting while in Figure 2 the clamp is against the track rail.

It will be observed that such construction embodies only two units; one the replacer 50 casting, and the other the clamping member. There are no parts to become lost or displaced and spikes, bolts and the like are unnecessary. It will be noted that my invention is especially adaptable for securing replacers to industrial railways such as are used in yards of large manufacturing plants where sometimes the rails are unsupported by ties, and also in industrial railways where 55 steel ties are used of very shallow depth, it being manifestly impossible to drive spikes through metal ties; therefore, my invention 60

may be readily utilized in such track construction.

While I have described more or less precisely the details of construction of my invention, I do not wish to be understood as limiting myself thereto as I contemplate changes in form and proportion of parts and the substitution of equivalents as circumstances may suggest or render expedient 65 without departing from the spirit of my invention.

I claim:

1. A car replacer including a replacer casting having lugs adapted to contact the rail web, a clamp for securing the casting to a rail including a strap adapted to underlie the casting and the rail base and hook over an edge of one of said members, and a cam supported in the other end of said strap adapted to wedge against the element not engaged by the hook end of the strap for securing the casting to the rail.

2. A car replacer including a replacer casting and a clamp member, said clamp including a strap adapted to underlie the casting and rail, and having an end arranged for hooked engagement with either of said members, a cam on the other end of said strap adapted to be wedged against the member not engaged by the hooked end of the strap, and means for actuating the cam.

3. A car replacer including a replacer casting and a clamp for removably securing the same to a track rail, said clamp comprising a metal strap adapted to underlie the casting and rail, and having one end arranged as a hook; the other end being provided with a cam mounted on a vertical axis, the parts being arranged whereby the hooked end of the strap may engage either the casting or rail, while the cam engages the other of said members in such a manner that when the cam is wedged against one of said members the casting may be drawn and held tightly 100 against the rail.

4. A car replacer including a replacer casting and a clamp, said casting having portions adapted to rest on the rail base and other portions adapted to contact the rail web, said clamp including a strap adapted to extend underneath the casting and rail and having an end formed as a hook for engaging with the casting or rail flange, the other end being provided with a cam adapted to be moved into wedging engagement with the member not hooked to hold the casting against the rail for replacement purposes.

Signed at Chicago, Illinois, this 23rd day 120 of February, 1922.

RICHARD D. GALLAGHER.
